POWER TRANSMISSION

Ferris T. Harrington, Clifford V. Losey, and Raymond S. Miller, Detroit, Mich., assignors to Vickers Incorporated, Detroit, Mich., a corporation of Michigan

Application July 13, 1939, Serial No. 284,208

7 Claims. (Cl. 200—82)

The present invention relates to power transmission of the hydraulic type and particularly to a pressure switch for use in power transmissions of this character. Such a power transmission generally comprises a source of pressure, such as a pump, together with one or more fluid motors which are driven by pressure fluid supplied from the pump. Control means such as directional valves are usually provided for selectively controlling the flow of fluid to the motor, and such control means are frequently operated electrically as by solenoids.

It is frequently desirable to shift such control means in dependence upon the rise in pressure at a certain point in the system, and for this purpose pressure switches have heretofore been employed. One of the most common control systems of this type utilizes a pressure switch hydraulically connected with the pressure side of a hydraulic motor so that the switch is operated when a predetermined pressure is applied to the motor. Since the pressure applied to the motor depends entirely upon the resistance which the motor encounters in doing its work and since this resistance is subject frequently to momentary fluctuations of varying magnitude, considerable difficulty is frequently encountered with pressure switches of the prior art due to their responding to these momentary fluctuations at a time when no response is desired, thus producing faulty operation of the system.

The number of different possible hydraulic circuits in which a pressure switch may be used is almost countless, each circuit requiring slightly different characteristics in the pressure switch for satisfactory operation. It is desirable in the manufacture of a line of pressure switches for use in this field to have as few different models as possible and yet to be able to provide a pressure switch having suitable characteristics for any particular circuit application which may be proposed.

It is an object of the present invention accordingly to provide an improved pressure responsive switch which is adapted for installation in circuits having widely different characteristics and which may be made to respond to pressure rises of any desired degree and of any desired speed.

A further object is to provide a pressure switch of this character of simple and reliable construction which is inexpensive to manufacture and which is readily adaptable to various conditions by a simple substitution of inexpensive parts

readily accessible from the outside of the switch mechanism.

Further objects and advantages of the present invention will be apparent from the following description, reference being had to the accompanying drawing wherein a preferred form of the present invention is clearly shown.

In the drawing:

Figure 1 is a longitudinal cross section of a pressure switch embodying a preferred form of the present invention.

Figure 2 is a cross section on line 2—2 of Figure 1.

Figure 3 is a fragmentary cross section corresponding to a portion of Figure 1 showing a modified form of the end cap illustrated in Figure 1.

20 A main body member 10 is provided with a longitudinal bore 12 having an enlarged chamber 14 at the upper end thereof and an oil seal 16 at the lower end thereof. Slidably mounted within the bore 12 is a piston 18. The latter has an annular groove 20 substantially at its mid portion and an annular groove 22 near the upper end thereof. A flange 24 provided with one or more fluid conducting notches 26 at the lower corner thereof is provided at the top end of the piston 18. The piston 18 is formed with one or more passages connecting the annular grooves 20 and 22. In the form illustrated this passage is formed as a flat 28 (Figure 2), only one such passage being illustrated, thereby providing a path of predetermined resistance between the chamber 14 and the annular groove 20.

35 The bore 12 is provided with a lateral outlet port 30 in which an interchangeable bushing 32 is mounted. The latter serves as a pipe connection to which a suitable conduit may be screwed for draining fluid to the usual oil sump. The bushing 32 is provided with a small orifice 34 of predetermined resistance, it being understood that bushings having orifices 34 of different size may be readily substituted for that shown in the drawing.

45 Secured to the lower face of the body 10 by a suitable fastening means, not shown, is a switch enclosure 36 carrying a suitable snap-acting, double-throw switch generally designated as 38, the details of which per se form no part of the present invention. Slidably mounted in holes 40 in the casing 36 is a switch-operating plunger 42 which is biased to an upward position illustrated by a suitable spring 44. Mounted between the top of the housing 36 and the upper end of a bore 46 in the piston 18 is a spring 48 which

normally biases the piston 18 to the upper position illustrated, a suitable spring-guiding stud 50 being mounted at the upper end of spring 48 and providing a predetermined clearance at 52 with the upper end of plunger 42.

Secured to the upper end of the body 10 is a cap member 54 having a conduit connection 56 at the upper end thereof adapted to receive a bushing 58 similar to the bushing 32 except that it is provided with a larger orifice 60 than the orifice 34. Communicating with the connection 56 is a transverse passage 62 having a valve seat 64 therein adapted to receive a ball valve 66. The latter is urged to the seat by a spring 68 which is adjustable by means of a threaded abutment plunger 70. A vertical passage 72 connects between the chamber 74, in which the ball 66 and spring 68 are mounted, and the chamber 14 in body 10.

In operation, the bushing 58 having been connected to the point in the hydraulic system at which a pressure rise occurs and to which rise the switch is to respond, it will be seen that a predetermined rise in pressure in the connection 56 and conduit 62 will lift the ball 66 from its seat. The pressure at which this occurs depends upon the setting of the spring 68 which may be readily adjusted by the plunger 70.

When the ball 66 lifts, pressure fluid is admitted to the chamber 14 through conduit 72. There is, however, a path of escape from the chamber 14 through the passageway 28 to the annular groove 20 and through orifice 34 and connection 32 to the sump. This path is restricted, however, by the passage 28 to a limited degree and by the orifice 34 to a larger degree. Thus it will be seen that in order for the piston 18 to move downwardly against the force of the spring 48 it is necessary that such pressure exist in conduit 62 as will lift the ball 66 far enough to pass oil into chamber 14 at a greater rate than it can pass out through orifice 34. Whenever this pressure is exceeded, the piston 18 will move down taking up the clearance at 52 and thereafter depressing plunger 42 to shift the switch 38.

As soon as the pressure in conduit 62 falls below the point where the piston 18 has started moving, the latter will start to move upwardly permitting spring 44 to lift the plunger 42 and restore the switch 38 to its original position. During this action the ball valve 66 closes and the oil displaced from chamber 14 escapes through the passage 28 and orifice 34 to the sump.

It will be seen that by substitution of bushings 32 having orifices of smaller or greater size that the relationship between the speed of rise of pressure in conduit 62 and the speed of movement of piston 18 may be controlled as desired. It is preferred to utilize the single passageway 28 in the piston 18, thus acting as a minimum restriction between chamber 14 and connection 32 which may be utilized for slowing down the piston movement to a maximum extent 65 by providing a bushing 32 with an orifice of negligible resistance.

Still further control of the speed of movement of piston 18 may be obtained by substituting for the bushing 58 one having a smaller orifice 60, thus limiting the speed at which sudden pressure rises in the conduit beyond bushing 58 may be transmitted to the conduit 62. The smaller orifice 60 must, however, be one which has less resistance than the combined resistance of the 70

passage 28 and the particular orifice 34 being used.

Certain applications require that when the switch 38 is once operated by a pressure rise transmitted to the piston 18, the switch must remain in its shifted position until the pressure in conduit 62 has dropped practically to zero. For this purpose a modified form of end cap 54 may be substituted in place of that shown in Figure 1, the modified construction being illustrated in Figure 3. The end cap 54' there shown is identical with the end cap 54 of Figure 1 except that an additional passage 74 communicates with the passage 72' and is provided with a valve seat 76. A ball valve 78 cooperates with the seat 76 and is lightly urged to closed position by a light spring 79. The chamber 80 in which the ball and spring are mounted communicates with the conduit 62' and the connection 56 by a branch conduit 82. Thus the ball 78 acts as a check valve preventing flow from connection 56' to conduit 72' except through the ball valve 66'.

When the modified end cap 54' is utilized, a modified piston construction is also utilized in place of the piston 18, this modification consisting merely in the omission of the flat 28, thus sealing the chamber 14 from the drain connection 32. The latter may be provided with an orifice of practically any size whatever since it is no longer critical in the operation of the switch and serves merely to drain seepage which occurs along the cylindrical surface of piston 18 and thus prevent pressure from building up on the packing 16. The coupling 58' may be provided with as small an orifice as may be desired.

The operation of this form of the invention is similar to that previously described except that when the pressure in the conduit 62' has risen sufficiently to open valve 66', the entire quantity of oil delivered therethrough is utilized to displace the piston 18 and shift the switch-operating plunger 42. As soon as the piston 18 has moved downwardly through its full stroke, the valve 66' again closes due to equalization of pressure on opposite sides thereof. Upward movement of the piston is prevented until the pressure in connection 56' falls to the point where check valve 78 may open, thus permitting oil to discharge from the chamber 14 through passages 74 and 82 to the connection 58'.

It will be noted that with either form of the invention small momentary pressure surges such as are bound to occur in many types of hydraulic systems will not depress the piston 18 sufficiently to shift the switch 38. In the first form of the invention described this result arises from the provision of the restricted drain to the chamber 14 which thus necessitates a supply of oil through the valve 66 in greater quantity than can escape from chamber 14 through the drain connection 32. In the second form of the invention momentary pressure surges are prevented from operating the switch by the provision of the clearance at 52. This permits the piston 18 to move downwardly a small amount without actuating the plunger 42. Also, due to the provision of a snap-acting switch some downward movement of the plunger 42 may be permitted before the switch is actuated. It will thus be seen that there is provided a pressure switch mechanism which is adapted to meet many varied requirements encountered in hydraulic transmission systems by the ready substitution of the simple and inexpensive bushings 32 and 58 and which may be

conveniently adjusted as to its pressure response by adjustment of the spring plunger 10.

It will further be seen that the construction disclosed provides a switch which responds quickly to significant sustained pressure rises but which, on the other hand, is not affected by momentary pressure surges, even though they may rise to a value equal to or greater than the sustained pressure rise required to operate the switch.

While the form of embodiment of the invention as herein disclosed constitutes a preferred form, it is to be understood that other forms might be adopted, all coming within the scope of the claims which follow.

What is claimed is as follows:

1. A pressure responsive electric switch comprising a body member enclosing an expandible chamber having a movable element, a snap-acting electric switch connected for operation by said movable element, a passage communicating with said chamber to form an inlet conduit adapted to be connected with a variable pressure source, a second passage communicating with said chamber at all times to form a continuously open outlet duct and adapted to be connected to a drain, a spring-loaded pressure responsive valve in said first passage and adapted to maintain said passage closed at pressures below a predetermined degree, and a readily replaceable bushing in said second passage at the outside of said body.

2. A pressure responsive electric switch comprising a body member enclosing an expandible chamber having a movable element, a snap-acting electric switch connected for operation by said movable element, a passage communicating with said chamber to form an inlet conduit adapted to be connected with a variable pressure source, a second passage communicating with said chamber at all times to form a continuously open outlet duct and adapted to be connected to a drain, and a spring-loaded pressure responsive valve in said first passage and adapted to maintain said passage closed at pressures below a predetermined degree, said second passage having sufficient fluid resistance to prevent actuation of the switch upon momentary pressure surges passing said valve.

3. A pressure responsive electric switch comprising a body member enclosing an expandible chamber having a movable element, a snap-acting electric switch connected for operation by said movable element, a passage communicating with said chamber to form an inlet conduit adapted to be connected with a variable pressure source, a second passage communicating with said chamber at all times to form a continuously open outlet duct and adapted to be connected to a drain, a spring-loaded pressure responsive valve in said first passage and adapted to maintain said passage closed at pressures below a predetermined degree, and a pair of interchangeable bushings in said passages, accessible from the outside of the body and providing predetermined resistance to flow therethrough.

4. A pressure responsive electric switch comprising a body member enclosing an expandible chamber having a movable element, means pro-

viding a non-adjustable resilient bias for said movable element, a snap-acting electric switch connected for operation by said movable element, a passage communicating with said chamber to form an inlet conduit adapted to be connected with a variable pressure source, a second passage communicating with said chamber at all times to form a continuously open outlet duct and adapted to be connected to a drain, and an adjustable, spring-loaded, pressure responsive valve in said first passage and adapted to maintain said passage closed at pressures below a predetermined degree, said outlet passage being provided with a mounting to receive any of a plurality of different sized restrictor bushings.

5. A pressure responsive electric switch comprising a body member enclosing an expandible chamber having a movable element, means providing a non-adjustable resilient bias for said movable element, a snap-acting electric switch connected for operation by said movable element, a passage communicating with said chamber to form an inlet conduit adapted to be connected with a variable pressure source, a second passage communicating with said chamber at all times to form a continuously open outlet duct and adapted to be connected to a drain, and an adjustable, spring-loaded, pressure responsive valve in said first passage and adapted to maintain said passage closed at pressures below a predetermined degree, said inlet passage being provided with a mounting to receive any of a plurality of different sized restrictor bushings.

6. A pressure responsive electric switch comprising a body member enclosing an expandible chamber having a movable element, a cover member removably secured to said body and forming a closure for said expandible chamber, a snap-acting electric switch connected for operation by said movable element, a passage in said cover communicating with said chamber to form an inlet conduit adapted to be connected with a variable pressure source, a second passage in one of said members communicating with said chamber at all times to form a continuously open outlet duct, a spring-loaded pressure responsive valve in said first passage and adapted to maintain said passage closed at pressures below a predetermined degree, and a readily replaceable bushing in one of said passages at the outside of said body.

7. A pressure responsive electric switch comprising a body member enclosing an expandible chamber having a movable element, a snap-acting electric switch connected for operation by said movable element, a passage communicating with said chamber to form an inlet conduit adapted to be connected with a variable pressure source, a second passage communicating with said chamber at all times to form an outlet duct, a spring-loaded pressure responsive valve in said first passage and adapted to maintain said passage closed at pressures below a predetermined degree, and a check valve in said second passage and in parallel with said pressure responsive valve.
